MULTIPLE COMPLETION PUMPING UNIT
Levon Z. Halimark, P.O. Box 484, Andrews, Tex.
Filed Dec. 14, 1962, Ser. No. 244,674
4 Claims. (Cl. 103—212)

This invention relates generally to pumping units for oil wells, and more particularly to multiple completion pumping units installed on dual, triple and quadruple oil well completions. Although the fundamental purpose of the present invention is a pumping unit to be used in multiple sucker rod string completions, the same may also be readily adapted to single completions as well.

The multiple completion pumping unit hereinafter described eliminates the use of such components which are generally known by oil men as horse's heads, walking beams, sampson posts, etc. This invention provides for the elimination of the old components and their replacement by new components which are more compact, are easy to operate and present fewer safety hazards. For instance as compared to conventional pumping units, the present multiple completion pumping unit does the job just as effectively yet with much saving in time, labor and oil production loss when remedial work becomes necessary.

In actual practice, a dual completion well using two single sucker rod strings of conventional design, it is necessary that both pumping units be shut down, partially disassembled and laid aside in order to pull only one rod string. This is a time consuming and costly operation. More importantly, the rod string that is still in good condition and does not require remedial work must lose its production while the faulty string is being repaired. In addition, on a dual completion well having one flowing side and one pumping side, the pumping side must be shut down in order to swab or cut paraffin in the flowing side. Only after all work has been completed may the pumping side be put back into operation. Likewise, on triple and quadruple completions, all strings must be shut down and disconnected to repair only one string.

Through the utilization of the present multiple completion pumping unit all of the above enumerated problems may be eliminated in the event of needed repairs to any one rod string or pumping unit. From the foregoing it becomes obvious that any one string of sucker rods may be pulled, fished, etc., if necessary without interrupting, even momentarily, the operation of any of the other rod strings. While under conventional methods of operation, all strings must be shut down and disconnected to repair only one string, under the new method production loss is eliminated and no time or labor is wasted. Moreover, the versatility of the new apparatus is such that it can easily be adapted to any type or size well head and may be installed on any location site.

Accordingly, one object of this invention is the provision of a multiple completion pumping unit that will eliminate waste in time and labor when remedial work is required.

Another object of this invention is the provision of a multiple completion pumping unit that is inexpensive to produce, easy to install and safe to operate.

Another object of this invention is the provision of a multiple completion pumping unit allowing any one string of sucker rods to be pulled, fished, serviced or repaired without interrupting the operation of any of the other sucker rod strings.

A further object of this invention is a provision allowing adjoining tubing strings to be swabbed or have paraffin cut without interrupting the operation of any sucker rod strings.

2

An additional object of this invention is the provision of a multiple completion pumping unit allowing adjoining Kobe tubing strings to be pulled, fished, serviced or repaired without interrupting the operation of any sucker rod strings.

Another object of this invention is a provision allowing stuffing boxes to be replaced or serviced without shutting down adjoining pumping units.

Another object of this invention is the provision of a multiple completion pumping unit that has no exposed moving parts at the well head vicinity.

A further object of this invention is the provision of a novel sheave housing assembly.

This invention consists of certain other features in construction and operation and in the combination and arrangement of several parts, to be hereinafter fully described, illustrated in the accompanying drawings and specifically pointed out in the appended claims.

In describing the invention in detail, references will be had to the accompanying drawings where like character numerals denote like or corresponding parts throughout the several views, and in which:

FIG. 1 is a side elevational view of the invention;

FIG. 2 is a side elevational view of FIG. 1;

FIG. 3 is a plan elevational view of FIG. 2;

FIG. 4 is an exploded perspective view of the sheave housing assembly;

FIG. 5 is a plan elevational view thereof; and

FIG. 6 is an exploded perspective view of a modified form of the handling straps.

As shown in the drawings, and more particularly referring to FIG. 1, the mounting base is preferably constructed out of concrete for a ground-level installation, whereas the structural steel supports or legs 11, along with the lower concrete footing is used for a cellar installation. An "I" beam platform 13, with adjustable leg screws is mounted on the concrete base to support the sheave housing assembly 12. From FIGS. 1 and 2, it can be seen that a pair of sheave housing assemblies 14 and 15 is mounted on the platform 13, each housing being connected to its respective tubing pump joint 16 and 16a respectively. The latter, by means of the unions 17 and 18 communicate the oil well proper with the flow lines 19 and 20 which lead to the storage tanks or to the refinery (not shown).

More particularly referred to FIG. 1, it shows the platform 13 mounted over the well head 21, which in turn by means of the threaded or flanged unions 22 and 23, is connected to the dual sheave housing assemblies 14 and 15. The pumping unit shown in FIGS. 2 and 3 may be of any conventional make as long as it includes a drive motor 24, the gear box 25, and the counterbalanced weights 26, which are held to the revolving head 27. The latter is mounted to rotate in bearings 28 in the gear box frame 25, being driven by the motor 24.

A pair of pitman arms 29 are by means of the pins 30 mounted eccentrically to the head 27 and in such a manner as to oscillate and transmit the oscillating motion of the pitman arms 29 to the rollers 31. The latter are slideably mounted in the roller tracks 32 of the pumping unit frame 33.

By means of a crossbar, or bridge 34, the oscillating motion of the pitman arms 29 with their rollers 31 is transmitted to the polished rod 35, which passes through the stuffing box 36, the thrust plate 37, and on through the pumping T 38. Both the thrust plate 37 and the pumping T 38 are connected to the tubing 16 (see FIG. 1). The thrust plate 37 butts against its adjustable companion thrust bearing, 62, which is a part of the pumping unit frame 33.

From the exploded perspective view in FIG. 4, it can be seen that while each of the sheave housing assemblies 14 and 15 is similar in its overall construction, they are mounted upon the platform 13 facing in opposite direction (see FIG. 1). One sheave housing assembly (namely 14) is by means of its coupling 39 connected to the tubing 16, while the other sheave housing assembly (numbered 15) is by means of its coupling 40 connected to its tubing 16a. Their respective threaded nipples 22 and 23 connect by means of the unions or threaded flange adapters, the sheave housing assemblies 14 and 15 to the oil well head 21. The sheave shaft 43 rests upon the platform 13 and receive the entire weight of their respective sucker rod strings 46.

Each of the sheave housing assemblies consist of a cast sheave housing 41, which is provided with bored holes 42 and grooved to receive O ring seals into which is mounted the sheave shaft 43. A sheave roller, or pulley 44, being fitted with roller bearings, is mounted to rotate on the sheave shaft 43 inside the sheave housing 41. From FIG. 4, it can be seen that a wire rope 45 has one end thereof 45a secured by means of a rope socket and swivel to the polished rod 35 (which is operated by means of the reciprocating motion of the pitman arms 29 above described); while the other end 45b is passed over the sheave roller 44 to enter the threaded nipple 22 and to connect by means of a second rope socket and swivel 45c to the nomal sucker rod string 46.

A plate 49, with its gasket seal 48, is mounted by means of the holes and screws 47 over the inspection opening 47a in the sheave housing 41. A handling strap 50, by means of holes 51 and 51a and the sheave shaft 43 is fastened to the sheave housing 41. With its opposite end 50a, the handling strap 50 is provided with a lifting eye 52. By means of the lifting eye 52, the handling strap 50 may be attached to any conventional crane hook or oil well serving unit to permit the lifting of the sheave housing assembly from the platform 13, in the event of replacements, repairs or remedial work to the oil well.

FIG. 6 shows a modification of the handling strap 50 shown in FIG. 4, wherein in this case the strap is provided with a pair of flat strap plates 53 and 54, which are mounted to the sheave shaft 43 by means of holes 55 and 56 respectively. In place of the lifting eye 52 (see FIG. 4), the present arrangement provides for a connecting tubular link or spacer 57, which by means of the bolt and nut 58 and 59 may be permanently secured to the plates 53 and 54 by holes 60 and 61, thus forming a modified handling strap shown in FIG. 6. The object of this modification of the handling strap is to provide an even lower silhouette of the entire sheave housing assembly in as much as the modified handling strap, when not in use, may, by removing the bolt and nut 58 and 59 and spacer 57, be folded back and down below the coupling 39 and tubing 16 and come to rest parallel to the platform 13 (see FIG. 1) where the spacer 57 and bolt and nut 58 and 59 may be replaced.

From the foregoing description of the device shown in FIGS. 1 to 6 inclusive, it becomes apparent that in actual operation and in the event remedial work has to be done to the dual complexion illustrated in FIG. 2, either of the sheave housing assemblies 14 or 15 may be readily removed for repairs or replacements without

in any way interfering with the operation of the adjoining sheave housing assembly.

A careful consideration of the foregoing description in conjunction with the invention as illustrated in the drawings will enable the reader to obtain a clear understanding and impression of the alleged features of merit and novelty sufficient to clarify the construction and operation of the invention as hereinafter claimed.

Minor changes in shape, size, materials and rearrangement of parts may be resorted to in actual practice so long as no departure is made from the invention as claimed.

What I claim as new and desire to protect by Letters Patent of the United States is:

1. A multiple completion unit of the class described for oil wells comprising in combination a pair of reciprocating arms, a reciprocating shaft mounted to said arms, oil well rods, a well platform, a sheave pulley, a pulley shaft, a wire rope of substantial length having one end thereof adapted to be connected to said reciprocating shaft with its other end being connected to said oil well rods, a sheave housing assembly mounted on said well platform and comprising a housing frame, said sheave pulley being mounted to turn on said shaft inside said frame, said wire rope passing over said pulley, said shaft in said frame while resting on said platform supporting the entire weight of said rods, means for securing said sheave housing assembly to said oil well platform, said sheave housing assembly having a threaded coupling connecting said assembly to a joint leading to a main oil well flow line, a tubing connected to said coupling and said wire rope passing through said tubing to enter the interior of the sheave housing assembly.

2. The combination according to claim 1; wherein multiple sheave housing units are mounted over said oil well head, and means to mount each unit separately on said platform, and means to secure each unit separately to said oil well head.

3. The combination according to claim 1; wherein said sheave housing assembly is provided with a handling strap formed from a pair of flat plates, said plates positioned on either side of the housing frame of said sheave, holes in said plates in alignment with the sheave shaft, said shaft passing through said holes in said plates, the opposite end of said plates cojoined together to form a yoke, said yoke being provided with a lifting eye.

4. The combination according to claim 1; wherein said sheave housing assembly is provided with an inspection opening, said opening being cut in one end of the housing frame, a cover plate and gasket over said opening, and screw means for securing said cover plate over said opening when the internal parts replacement or inspection thereof has been completed.
